Des. 241,393
Patented Sept. 14, 1976

241,393

AUXILIARY MUSIC HOLDER FOR ATTACHMENT TO A PIANO OR SIMILAR ARTICLE

Val St. Regis, 157 Geary St.,
San Francisco, Calif. 94108

Filed Jan. 30, 1975, Ser. No. 545,361

Term of patent 14 years

Int. Cl. D6—99

U.S. Cl. D6—184

FIG. 1.

FIG. 2.

FIG. 3.

FIG. 1 is a perspective view of an auxiliary music holder for attachment to a piano or similar article, showing my new design;

FIG. 2 is a front elevational view; and

FIG. 3 is a side elevational view.

I claim:

The ornamental design for an auxiliary music holder for attachment to a piano or similar article, as shown.
